CLAIM

The ornamental design for a triangular saturation pattern detection indicator for a patient monitor display panel, as shown and described.

DESCRIPTION

FIG. 1 is a perspective view of a triangular saturation pattern detection indicator for a patient monitor display panel shown in the environment of a partially shown pulse oximetry monitor;

FIG. 2 is a front view thereof, shown in the environment of a pulse oximetry monitor, where the triangular indicator is about three quarters full;

FIG. 3 is a front view thereof shown in the environment of a multi-parameter monitor; and,

FIG. 4 is a front view thereof, shown in the environment of a pulse oximetry monitor, where the triangular indicator is about half full.

The broken lines showing the display panel and portion of the patient monitor are for the purpose of illustrating unclaimed portions and form no part of the claimed design.
